Application May 16, 1952, Serial No. 19,738

Term of patent 14 years

(Cl. D14—24)

To all whom it may concern:

The invention described herein, if patented, may be manufactured and used by or for the Government for governmental purposes, without the payment to us of any royalty thereon.

Be it known that we, Frederick T. Paden and Alexander C. H. Weiss, both citizens of the United States, residing, respectively, at Collingswood, in the county of Camden and State of New Jersey, and at Chicago, in the county of Cook and State of Illinois, have invented a new, original, and ornamental Design for a Sled, of which the following is a specification, reference being had to the accompanying drawings, forming a part thereof.

Figure 1 is a perspective view of a sled showing our new design.

Figure 2 is a side elevation of the same.

Figure 3 is a central vertical longitudinal section through the sled.

Figure 4 is a rear end elevation of the sled, Figure 5 is a front end elevation of the same, Figure 6 is a plan view of the sled; and, Figure 7 is a bottom plan view of the sled. The dominant features of the design are shown in full lines.

We claim:

The ornamental design for a sled, substantially as shown and described.

FREDERICK T. PADEN.
 ALEXANDER C. H. WEISS.
